UNITED STATES PATENT OFFICE

JOHN HENIGE, OF CHICAGO, ILLINOIS

LIQUID TREATMENT COMB

Application filed November 14, 1930. Serial No. 495,683.

The device of my invention relates to means for supplying liquid, and particularly hot oil, to the roots of the hair, and is an improvement over my prior Patent No. 1,661,527 of March 6, 1928.

It is common practice to employ mechanical means for supplying liquid to the scalp, and likewise common to provide means for supplying hot oil to the scalp, but the manner 10 in which this has been accomplished in the past has been very crude, impractical and inefficient. This because of numerous structural defects in the apparatus which I believe I have eliminated in the device herein 15 illustrated.

The main object in a device of this character is to provide simple and efficient means for directly supplying hot oil to the very roots of the hair. The device herein 20 plies the oil directly through the apertured teeth in a free and unobstructed manner. It has been found impractical to provide the usual form of comb teeth with a fine enough discharge aperture therein, the result being 25 too great a flow of oil. The improved device therefore, provides individual hollow teeth of uniform diameter, a part only of said teeth having discharge openings, the number of discharge openings provided being 30 variable to suit individual requirements, if desired. In addition I may provide discharge openings on alternate sides of the teeth instead of all openings on one side, or two discharge openings in a single tooth. I 35 also contemplate providing the end teeth and some intermediate teeth of solid metal construction of the same cross section as the hollow teeth. Thus the danger of breakage of the relatively fragile hollow teeth is considerably 40 minimized. This is made possible by reason of the fact that only a few of the hollow teeth are ordinarily provided with discharge openings.

A further improvement in the present 45 structure is the provision for lateral discharge openings, in the sides of the apertured teeth, this for the reason that dandruff and foreign matter will not be likely to clog the discharge openings in the teeth, but will 50 be wiped off in passing through the hair. A

further advantage in providing side openings is that the size of the tooth aperture assumes less importance for the reason that the size of the discharge openings can be regulated to provide the flow desired much easier 55 than the passages within the teeth.

A further object of my invention is to provide a single, one-piece, hollow molded head having formed centrally within the cavity thereof a longitudinally extending chamber for the reception of the heating element, the outer end terminating in a projection to which the handle is secured. Thus no threading or fitting of the inner chamber to the head is necessary, and in addition the placing of 60 the inner chamber centrally within the head provides the greatest heat absorption efficiency. This for the reason that the heating chamber is only in contact with the oil, and the heat must first be communicated to the 65 oil before it can escape. Thus it is unnecessary to first heat a large amount of metal.

My invention will be more readily understood by reference to the accompanying drawings, in which:

Fig. 1 is a side elevation of my improved liquid treatment comb;

Fig. 2 is a longitudinal sectional view thereof, and

Fig. 3 is a horizontal sectional view taken 75 on the lines 3—3 of Fig. 2.

By reference to the drawings it will be seen that my comb comprises a hollow handle 10, having a recess at the outer end for the reception of electrical connecting means 11. The upper end of the handle 10 is adapted to fit snugly over the projection 12 formed as a part of the head or liquid reservoir 13, and to contact the shoulders 14 formed thereon.

The head 13 is preferably molded in one 80 single piece and provides a rest 15, filling opening 16, having the cap 17, and the centrally disposed, internal, hollow chamber 18, closed at its inner end, and open at its outer end, and adapted to receive electrical heating 85 means 19 operated by the wires 20 from the plug 11.

On one side of the head, opposite to the rest 15 the head is reduced in cross section, as best shown in Fig. 3. This portion 21 is 90

provided with a plurality of spaced apertures 22 for the reception of hollow tubing, having closed or imperforate ends. A portion of the teeth 23 are provided with side discharge openings 24. It is understood that the openings 24 may be formed on one or both sides of the teeth. It has also been found desirable to form one opening on opposite sides of alternate teeth, so that the openings are in 10 staggered relation. As a matter of protection to the relatively fragile teeth 23, I may provide solid teeth 25 at the ends, and if desired, between the ends, to replace the hollow teeth not having discharge openings.

15 It will thus be seen that I have provided a most compact and efficient article, capable of being readily and cheaply manufactured and assembled. Obviously modifications and variations may be made by those skilled in the 20 art, and I do not wish to be limited except as herein claimed.

I claim:

1. In a liquid treatment comb, the combination of a head having an internal cavity and 25 provided with a filling opening, a hollow cylinder projecting into said cavity and connected to the head only at the end opposite to said filling opening and projecting beyond said head, a handle fitted over said projection, 30 and electric heating wires extending longitudinally through said handle and into said cylinder contained wholly within said cylinder.
2. In a liquid treatment comb, the combination of a head having an internal cavity and provided with a filling opening, a hollow cylinder integral with said head and projecting into said cavity and connected to the head only at the end opposite to said filling 35 opening and projecting beyond said head, a handle fitted over said projecting end, and electric heating wires extending longitudinally through said handle and into said cylinder contained wholly within said cylinder.
- 40 3. A liquid treatment comb comprising in combination a hollow head having a filling opening at the outer end thereof, and electric heating means within the same, a handle therefor, and a plurality of independent teeth set into said head, said teeth being formed from tubes the passages therein communicating with the interior of said head.
4. A liquid treatment comb comprising in combination a hollow head having a filling 45 opening at the outer end thereof and electric heating means within the same, a handle therefor, and a plurality of independent, tubular teeth of uniform diameter from end to end set into said head, the passages therein 50 communicating with the interior of said head.

55 5. An article of the class described, comprising a one-piece head having a filling opening at one end and a plurality of teeth on one side, a hollow member within said head

having a longitudinal opening therein, open at the end opposite said filling opening, a handle for supporting said head, and electric heating means passing through said handle and occupying the interior of said hollow 70 member and contained wholly within said hollow member.

6. A head for liquid treatment combs consisting of a hollow casing, a hollow member centrally disposed within the cavity in said casing, the casing having a filling opening in one end and a tubular projection from the opposite end, the opening in said projection being co-extensive with the cavity in said hollow member, all said parts being formed in a single casting, and independent teeth set 75 into said head.

7. In a liquid treatment comb, the combination of a handle having a central aperture therein, a hollow head constituting a liquid receptacle, walls providing a compartment in the cavity in said head, a heating element within said compartment, and a plurality of hollow teeth, each separately and independently connected to said head and communicating with the cavity therein, said teeth having their outer ends imperforate and having apertures in the sides thereof adjacent the lower end.

8. A liquid treatment comb for the purpose described comprising in combination, a hollow handle, a hollow head adapted to contain a liquid, and having a filling opening at the outer end, a hollow cylinder having imperforate walls projecting into the hollow head and integral therewith, the cavity in the cylinder communicating with the opening in said handle, and a heating element projecting into said cylinder from the handle and wholly contained within the same.

9. A liquid treatment comb comprising in combination a hollow head having a filling opening at the outer end thereof, and electric heating means within the same, a handle therefor, and a plurality of independent teeth set into said head, said teeth being formed from tubes, the passages therein communicating with the interior of said head, the extremities of the teeth being imperforate, said teeth having discharge openings through a side wall.

10. In a liquid treatment comb, the combination of a handle having a central aperture therein, a hollow head constituting a liquid receptacle, walls providing a compartment in the cavity in said head, a heating element within said compartment, and a plurality of hollow teeth, each separately and independently connected to said head and communicating with the cavity therein, said teeth having their outer ends imperforate and having apertures in the sides thereof adjacent the lower end, the openings in alternate teeth being on opposite sides.

11. A liquid treatment comb comprising in

combination a hollow head having a filling opening at the outer end thereof, and electric heating means within the same, a handle therefor, and a plurality of independent teeth set into said head, said teeth being formed from tubes, the passages therein communicating with the interior of said head, and other teeth of solid form for greater strength.

10 12. A liquid treatment comb comprising in combination a hollow head having a filling opening at the outer end thereof, and electric heating means within the same, a handle therefor, and a plurality of independent teeth set into said head, said teeth being formed from tubes, the passages therein communicating with the interior of said head, the extreme teeth being of solid form.

15 In testimony whereof I have affixed my
20 signature.

JOHN HENIGE.
